UNITED STATES PATENT OFFICE.

WILLIAM H. MAICHLE, OF COHOCTON, NEW YORK, ASSIGNOR TO BEECH-NUT PACKING COMPANY, OF CANAJOHARIE, NEW YORK, A CORPORATION OF NEW YORK.

DESIGN FOR A DISPLAY STAND FOR CONFECTIONS.

Application filed July 15, 1922. Serial No. 3,099. Term of patent 7 years.

To all whom it may concern:

Be it known that I, WILLIAM H. MAICHLE, a citizen of the United States, residing at Cohocton, in the county of Steuben and State of New York, have invented a new, original, and ornamental Design for Display Stand for Confections, of which the following is a specification, reference being had to the accompanying drawing, forming a part thereof.

The figure is a perspective view of the display stand.

I claim:

The ornamental design for a display stand for confections, as shown.

WILLIAM H. MAICHLE.

Witness:

S. B. PLANTE, Jr.
